ENGINE STARTING APPARATUS

Herbal A. Thornburg and James V. Brown, Anderson, Ind., assignors to General Motors Corporation, Detroit, Mich., a corporation of Delaware

Application July 8, 1936, Serial No. 89,503

5 Claims. (Cl. 123—179)

This invention relates to apparatus for starting an internal combustion engine and particularly to the type of apparatus which comprises an electric motor and a pinion driven by motor and movable axially into mesh with the fly-wheel or other gear of the engine to be started. In this type of apparatus the pinion is withdrawn from the fly-wheel gear after the engine has been started.

It is one of the objects of the present invention to prevent engaging the motor-driven pinion with the engine gear in case the engine is running prior to moving the pinion into engagement therewith.

In the disclosed embodiment of this invention the present object is accomplished by providing a part adapted to make substantially noiseless contact with an end face of an engine flywheel and to be moved in response to contact with the moving flywheel into such position as to positively stop movement of the motor pinion into engagement with the flywheel gear.

The present invention is adapted for any sort of motor vehicle propelled by an internal combustion engine and is particularly useful on passenger busses of the type where the engine is located on the side or at the rear of the vehicle and so far from the driver's seat that the operation of the engine when idling is not audibly perceptible. It occasionally happens that the operator, believing that the engine has stopped, whereas in fact it is idling, will operate the starter control button causing the starter pinion to mesh with the fly-wheel gear. The engagement of the starter pinion with the flywheel gear while the engine is running produces a disagreeable noise and is damaging to the gear teeth. Such noise or damage is avoided by the use of the present invention.

Further objects and advantages of the present invention will be apparent from the following description, reference being had to the accompanying drawings wherein a preferred embodiment of the present invention is clearly shown.

In the drawings:

Figure 1 is in part a longitudinal sectional view of the starting apparatus embodying the present invention and in part a wiring diagram;

Figures 2 and 3 are sectional views taken respectively on the lines 2—2 and 3—3 of Figure 1;

Figures 4, 5, and 6 are fragmentary side views partly in section of the engine starter drive, showing the same in various positions; and

Figure 7 is in part an end view of the pinion and clutch assembly and in part a sectional view of the clutch, the end view being taken in the direction of the arrow 1a of Figure 6, the sec-

tional view being taken on the line 7—7 of Figure 6.

Referring now to Figure 1, numeral 20 designates the electric motor comprising a field winding 21, an armature 22 and brushes 23 and 24, the latter of which is grounded at 25. This motor drives the shaft 26 which is supported by bearings carried by the frame of the motor. The left end frame is not shown, but it will be understood to be attached to the left-hand end of the field frame 27 which carries the field winding 21. The right end frame or gear housing of the motor is designated by numeral 28, and it carries a bearing 29 for the right-hand end of the shaft 26. The shaft 26 is provided with longitudinal splines 30 which cooperate with longitudinal splines 31 provided in the sleeve 32 of the inner member or clutch cam 33 of an overrunning clutch. This clutch comprises also a driven member or shell 34 and a series of rollers 35 each of which is located between the inner cylindrical surfaces of shell 34 and a cam surface 33a which is not concentric with the shell. The surfaces 33a are so arranged with respect to the shell 34 that, as the clutch inner member 33 rotates clockwise as viewed by the arrow 36 in Figure 7, clockwise rotation will be imparted to the shell 34. Obviously the shell 34 may overrun in a clockwise direction with respect to the inner driving member 33 when one views it as shown in Figure 7. The clutch inner member 33 carries a bearing bushing 37 which is journaled on the reduced end portion 26a of the shaft 26. The portion 26a supports a bearing bushing 38 press-fitted into the hub of a starting motor pinion 39 which is adapted to move axially along the shaft portion 26a into mesh with the flywheel gear 40 of the engine to be started. The pinion 39 is drivingly connected with the shell 34 by providing the latter with an annular boss 41 into which are provided a series of depressions, each adapted to receive an end portion of a tooth of the pinion 39 when the pinion is fixed to the shell 34, as shown in Figure 1. To secure the pinion 39 to the shell 34 the pinion is provided with an annular flange 42 which is passed through a central orifice in the shell 34 and is riveted over against the shell 34, as indicated at 43.

This overrunning clutch and pinion assembly is moved along the shaft 26 by means of a pinion meshing means including shifter sleeve 50 provided with an annular groove 51 for receiving pins or studs 52 located on diametrically opposite sides of the sleeve 50 and carried by spaced arms 53 of a lever 54 pivoted upon a rod 55 carried by the frame 28. The rod 55 is surrounded by a coil 55

spring 56, one end 57 of which bears downwardly against the frame 28, as indicated by the arrow 57a and the other end 58 of which bears in the direction of the arrow 59 against a pin 60 carried by the lever 54. Counterclockwise rotation of the lever 54 causes the sleeve 50 to move toward the right, as shown in Figure 1. The sleeve 50 has a central bore 61 which has a sliding fit with the shaft 26 and has a part 62 provided with a central bore 63 having a sliding fit with respect to the sleeve 32. Between the right-hand end of part 62 and the left-hand end of a washer 64 surrounding the sleeve 32 and bearing against the clutch cam 33, there is located a coil spring 65 which normally is somewhat compressed. Spring 65, therefore, forces the part 62 a definite distance away from the washer 64 and clutch cam 33. The separation of the parts 62 from the parts 64 is limited by a wire split ring 66 which is snapped 20 into a groove provided by the sleeve 32 and which bears against a beveled surface 67 provided on the left-hand end of the part 62. The part 62 is joined with the main part of the sleeve 50 by an arcuate web 68 shown best in Figure 2. This web 25 68 is spaced from the shaft 26 sufficiently to permit assembling the split ring 66. Quite obviously, motion of the sleeve toward the right as effected by counterclockwise rotation of the lever 54 will cause the motion to be imparted through the 30 spring 65 to the clutch and pinion assembly thereby causing the pinion 39 to move into engagement with the engine gear 40.

The lever 54 is moved in a counterclockwise direction by direct manual operation or by the 35 electromagnetic means shown diagrammatically in Figure 1. This electromagnetic means comprises an electromagnet having two windings 70 of relatively fine wire and 71 of relatively coarse wire. These windings surround a non-magnetic 40 tube 72 which provides a guide for the movement of a magnetizable armature 73 toward a stationary magnetizable core member 74 also located within the magnetic field which is created by current passing through these windings. The core 45 74 is attached to the magnetizable discs 75 which are in contact with a magnetizable shell 76 and in contact also with magnetizable discs 77 and 78 which are held by the sleeve 72 concentric with respect to the armature 73.

The starting motor 20 is energized by current 50 from a storage battery 80 which is grounded at 81 and which is connected by wire 82 with a starter switch contact 83. Contact 83 is connected by a movable contact 84 with a stationary contact 85 which is connected with winding 71 and with the series field 21 of the starting motor. The contact 84 is insulatingly supported by a tubular metallic rivet 86 which is slidable upon a rod 87 which extends through the core 74 and is guided 55 thereby. The rod 87 carries a washer 88 against which the tubular rivet 86 is urged by spring 89 located between a washer 90 fixed to the rod 87 and a washer 91 loosely mounted on the rod 86. The washer 90 is held against the left end face of core 74 by a spring 92 which surrounds a stud 93 carried by a fixed part 94 and projects into an axial bore 94 in the pin 87. The spring 92, therefore, serves to maintain the contact 84 out of engagement with contacts 83 and 85, and the right-hand end of plunger 87 in such position as to be normally engaged by the left-hand end of core 73. The winding 70 is grounded at 78.

The armature 73 is centrally tapped to receive the threaded shank 100 of a stud 101 which is 75 connected by cross pin 102 with a link 103 having

an elongated slot 104 through which passes a pin 105 connecting the link 103 with the lever 54. The two windings 70 and 71 are connected with the battery 80 by push-button switch 110.

To start the engine, the operator closes the switch 110 thereby causing the current to flow from the battery through the switch and through the windings 70 and 71 and back to the ground connection 70a. Current will also flow from the battery through the switch 110, winding 71, starting motor 20, and back to the battery through the ground connections 25 and 81. The electromagnet will be energized sufficiently to cause the armature 73 to move toward the left in order to cause that counterclockwise rotation of the lever 54 and that axial movement of sleeve 50 which will move the motor pinion 39 into mesh with the engine gear 40. During this movement of the armature 73, it will engage the rod 87 to cause it to move toward the left and the contact 84 to be engaged with the contacts 83 and 85 under yielding pressure afforded by the spring 89. When this occurs the motor will receive current from the battery and the shaft 26 will rotate and the pinion 39 will drive the engine gear 40 in such direction as to cause the engine to be started. After the engine has been started the operator releases the push-button switch 110 thereby causing the electromagnet to be deenergized, whereupon the lever 54 is moved clockwise into its original position due to the action of the spring 56, and the pinion 39 is withdrawn from the engine gear 40. The armature 73 having been withdrawn from the rod 87, the spring 92 moves the rod 87 back to its normal position thereby disengaging the contact 84 from the contacts 83 and 85, whereupon the motor 20 is disconnected from the battery 80 and the motor stops.

When the contact 84 engages the contacts 83 and 85 the winding 71 of coarse wire will be short circuited so that a greater amount of current will flow from the battery to the starting motor than before. At the time contact 84 engages with contacts 83 and 85 to short circuit the winding 71 the air gap between the core 74 and armature 73 is relatively small and, therefore, the magnetic force produced by the coil 70 alone is sufficient to hold the armature 73 in its attracted position.

Should the pinion 39 collide with the end faces of the teeth of the flywheel gear 40 before going into mesh, motion of the armature 73 will not cease due to the fact there is yielding connection afforded by the spring 65 between the sleeve 50 and the pinion and clutch assembly. After the pinion 39 engages the end faces of the teeth of the flywheel gear 40, the armature 73 will continue to move toward the left and the sleeve 50 toward the right. While the spring 65 is being compressed beyond its initial stage of compression, the switch contact is being engaged with the contacts 83 and 85. When this engagement occurs, the motor will be connected with the battery and will cause the pinion teeth to be brought into mesh registration with the spaces between the teeth of the engine gear 40. At the instant meshing registration occurs, the spring 65 will be released quickly to move or "jump" the pinion 39 into mesh with the engine gear 40.

Should the pinion 39 fail to come out of mesh with the engine gear 40 after the engine starts, the spring 92 is still free to move the contact 84 away from the contacts 83 and 85 due to the fact that the slots 104 in links 103 provide the lost-motion connection between the lever 54 and the armature 73.

The means for preventing the meshing of the motor pinion with the engine gear after the engine becomes self-operative and the pinion has been demeshed therefrom, will now be described with particular reference to Figures 1, 4, 5, and 6. This means comprises a tubular cup-shaped part 120 having a tubular sleeve 121 journaled on the part 62 of the sleeve 50 of the pinion meshing means, and having an annular flange 122 adapted to engage the left end face of the flywheel 123 which carries the gear 40. The part 62 carries diametrically opposed screw pins 124, each of which is received by a somewhat T-shaped slot 125 provided in the tubular sleeve 121 of the tubular part 120. The head of this T-shaped slot 125 is a somewhat triangular opening defined by wall portions 126 which are oblique or inclined to the axis of the pinion. The stem or elongated portion of the slot is indicated by numeral 127, and is of a length such that the pinion may be meshed with the engine gear while part 120 is pressed against an end face of the engine gear, provided that the pin 124 remains in alignment with the elongated slot portion 127. Where the stem or elongated portion 127 joins the head portion defined by oblique wall portions 126, the metal of sleeve 121 provides stop shoulders 128 each of which is adapted to receive pin 124 depending on which direction the sleeve 120 is rotated with respect to the sleeve 50.

Normally each pin 124 rests in the apex of the head portion of the slot 125 and between the oblique wall portions 126, and is caused to be moved into that position by spring 130 located between a shoulder 131 of the sleeve 50 and a washer 132 surrounding the sleeve 50 and bearing against the left end of the sleeve 121. Therefore, while the engine is at rest, the pinion 39 may be meshed with the engine gear 40 without hindrance by the cup-shaped member 120 since, during this meshing movement, the pin 124 will move into the stem portion 127 of the slot 125 and finally into the position shown in Figure 5, when the pinion 39 is fully meshed with the engine gear 40. During the cranking of the engine the flange 122 of the cup-shaped member 120 will bear against the left face of the engine flywheel 123, but such engagement will be practically noiseless.

If the operator attempts to mesh the motor pinion 39 with the engine gear 40 while the engine is running the tubular, cup-shaped part 120 will be rotated due to the frictional engagement of the end face of the flywheel 123 and flange 122 of the part 120 thereby causing the slots 125 in the sleeve 121 to be shifted relative to the pins 124 carried by the sleeve 50, one way or the other depending on the direction of the rotation of the cup-shaped member 120. Figure 6 shows the condition which will obtain if, looking in the direction of the arrow 1a in Figure 6, the rotation of the flywheel 123 is counterclockwise. Quite obviously, the rotation of the tubular, cup-shaped part 120 will be clockwise. Therefore, the slot 125 nearest the observer of the view shown in Figure 4 will move upwardly into the position shown in Figure 6, and the lowermost portion of the two shoulders 128 provided by the metal of the sleeve 121 adjacent the slot 125 will provide a stop for the pin 124. Since the pin 124 can move no further toward the right than is shown in Figure 6, the shifter sleeve 50 and the clutch and pinion assembly can be moved no further toward the right. The clutch and pin assembly is arrested in its movement and is lim-

ited to a position wherein the pinion 39 is still out of engagement with the left end faces of the gear teeth of the flywheel gear 40, as shown in Figure 6. In this way motion of the pinion into engagement with the engine flywheel gear is positively arrested when the operator attempts to mesh these gears while the engine is running.

Upon release of the operating lever 54 the spring 56 restores it and the other parts of the pinion meshing means to normal position shown in Figure 1. During this return movement, the end flange 122 of the tubular part 120 leaves the end face of the engine gear 123 and each slot part 127 returns to alignment with each pin 124 due to the camming action between each pin 124 and each inclined wall surface 126 caused by pressure exerted by the spring 130.

While the embodiment of the present invention as herein disclosed, constitutes a preferred form, it is to be understood that other forms might be adopted, all coming within the scope of the claims which follow.

What is claimed is as follows:

1. Engine starting apparatus comprising, in combination, an electric motor, a pinion driven by the motor and slidably axially into mesh with a gear of the engine to be started, means to move the pinion into mesh with the engine gear, and means responsive to rotation of the engine gear for positively blocking movement of the pinion into mesh with the engine gear while the engine is running, said last mentioned means comprising a locking sleeve adapted to be rotated by the engine gear into locking position to prevent movement of the pinion toward the engine gear.

2. Engine starting apparatus comprising, in combination, an electric motor, a pinion driven by the motor and slidably axially into mesh with a gear of the engine to be started, means to move the pinion into mesh with the engine gear, a part movable against an end face of the engine gear and adapted to be rotated thereby, means for transmitting movement from the pinion meshing means to said part to cause the latter to be pressed against an end face of the engine gear before the pinion starts to mesh with the engine gear, and devices for interconnecting the pinion meshing means and said part, said devices being so constructed and arranged as normally to permit such a relative movement between the pinion and part that the pinion may be meshed with the engine gear while the part is pressed against the engine gear and to prevent said relative movement in case the engine gear is rotating before the pinion is meshed therewith.

3. Engine starting apparatus comprising, in combination an electric motor, a pinion driven by the motor and slidably axially into mesh with a gear of the engine to be started, means to move the pinion into mesh with the engine gear, a tubular part surrounding the pinion and pinion meshing means and movable against an end face of the engine gear to be rotated thereby, means for transmitting motion from the pinion meshing means to said part to cause the latter to be pressed against an end face of the engine gear before the pinion starts to mesh with the engine gear, and devices for interconnecting the pinion meshing means and said part and provided respectively by said means and part, one of said devices being a laterally extending pin and the other a member having a slot for receiving the pin, said slot having an elongated portion extending longitudinally of the axis of the pinion whereby normally

to permit such a relative movement between the pinion and tubular part that the pinion may be meshed with the engine gear while the part is pressed against the engine gear, said slot providing a stop shoulder which is moved into alignment with the pin in case the tubular part is rotated by the engine gear face prior to the meshing of the pinion with the engine gear.

4. Engine starting apparatus comprising, in combination, an electric motor, a pinion driven by the motor and slideable axially into mesh with a gear of the engine to be started, means to move the pinion into mesh with the engine gear, a tubular part surrounding the pinion and pinion meshing means and movable against an end face of the engine gear to be rotated thereby, yielding means for transmitting motion from the pinion meshing means to said part to cause the latter to be pressed against an end face of the engine gear before the pinion starts to mesh with the engine gear, and devices for interconnecting the pinion meshing means and said part and provided respectively by said means and part, one of said devices being a laterally extending pin and the other a member having a slot for receiving the pin, said slot having an elongated portion extending longitudinally of the axis of the pinion whereby normally to permit such a relative movement between the pinion and tubular part that the pinion may be meshed with the engine gear while the part is pressed against the engine gear, said slot providing a stop shoulder which is moved into alignment with the pin in case the tubular part is rotated by the engine gear face prior to the meshing of the pinion with the engine gear, said slot having a surface oblique to the axis of the pinion whereby said surface and said yielding means may cooperate to restore the

pin to alignment with the elongated portion of the slot when the pinion meshing means returns to normal position.

5. Engine starting apparatus comprising, in combination, an electric motor, a pinion driven by the motor and slideable axially into mesh with a gear of the engine to be started, means to move the pinion into mesh with the engine gear, tubular part surrounding the pinion and pinion meshing means and movable axially against an end face of the engine gear to be rotated thereby, a slot provided by the tubular part including an elongated portion extending longitudinally of the axis of the pinion a pin extending laterally from the pinion meshing means and into said slot, a spring for transmitting motions from the pinion meshing means to the tubular part thereby causing one end wall of the slot of the tubular part to bear normally against said pin whereby normally to maintain an end of the tubular part closer to the engine gear than the pinion, said elongated slot portion permitting the pinion to be meshed with the engine gear while the tubular part is pressed against an end face of the engine gear, said slot providing a stop portion which is moved into alignment with the pin in case the tubular part strikes the engine gear while rotating whereby to prevent contact between the pinion and engine gear while the engine is running, and said slot providing a surface inclined to the axis of the pinion and located between the stop shoulder and an end of said slot, said inclined slot portion cooperating with the pinion under pressure exerted by said spring to restore the alignment between the pin and the elongated portion of said slot when the pinion meshing means returns to normal position.

HERBAL A. THORNBURG.
